UNITED STATES PATENT OFFICE

2,471,250

SELF-OPENING DIE HEAD

Royce M. Strickland, New Haven, Conn., assignor
to The Geometric Tool Company, New Haven,
Conn., a corporation of Connecticut

Application May 11, 1945, Serial No. 593,209

4 Claims. (Cl. 10—95)

1

The present invention relates to improvements in self-opening die-heads, i. e., die-heads which are provided with a plurality of thread-cutting chasers which latter, upon the completion of the threading operation, are retrievable out of engagement with the threaded workpiece in order to permit the direct axial separation of the die-head and the work-piece without requiring the reverse relative rotation thereof.

The present invention involves improvements upon the self-opening die-head disclosed in United States Patent No. 2,135,067 granted November 1, 1938, on the application of A. F. Breitenstein, and has for one of its main objects the overcoming of certain objections inherent in the structure of the said Breitenstein patent.

More particularly and like the structure of the said Breitenstein patent, the present invention relates to self-opening die-heads of the character which may be employed for cutting pipe-threads or other tapered threads and which rely upon the inclination of the series of thread-cutting teeth of the normally-stationary thread-cutting chasers, in order to thread the work-piece at the desired angle of taper in contradistinction to thread-cutting tools which progressively retire their chasers during the normal thread-cutting operation in order to effect the desired taper.

It may here be noted that one of the main objections which has been found to the self-opening die-head disclosed in the aforesaid Breitenstein patent, has been that after a relatively-brief period of use the latch-member has failed to remain in its latching position, apparently due to vibration coupled with an inherent tendency for the said latch-member to retire inwardly under the force exerted by the chaser-operating sleeve. It is another object of the present invention to provide a superior self-opening die-head which will overcome the objections just referred to in a simple, reliable and effective manner.

A further object of the present invention is to provide a superior self-opening die-head of the character referred to which will produce tapered threads free from abrupt shoulders extending longitudinally of the work-piece.

With the above and other objects in view, as will appear to those skilled in the art from the present disclosure, this invention includes all fea-

2

tures in the said disclosure which are novel over the prior art.

In the accompanying drawings, in which certain modes of carrying out the present invention are shown for illustrative purposes:

Fig. 1 is a view in side elevation of one form of self-opening die-head embodying the present invention, with the parts shown in the positions which they assume when in readiness to cut a taper-thread upon a work-piece;

Fig. 2 is a view thereof in front elevation;

Fig. 3 is a view thereof in rear elevation;

Fig. 4 is a broken longitudinal sectional view taken on the line 4—4 of Fig. 2;

Fig. 5 is a similar view but taken on the line 5—5 of Fig. 2;

Fig. 6 is a transverse sectional view taken on the line 6—6 of Fig. 1 but on a larger scale;

Fig. 7 is a broken central-longitudinal sectional view with the forward part in section on the line 7—7a of Fig. 2, and the part to the rear of the head-portion of the body-member taken on the line 7—7b of Fig. 2, but on a larger scale than the latter figure;

Fig. 8 is a view similar to Fig. 7 but showing the parts in the positions which they assume at the instant that the latch-member has reached the point at which the full retirement of the chasers is about to take place;

Fig. 9 is a perspective view of the latch-carrying ring, detached;

Fig. 10 is a similar view of the latch-member, detached; and

Fig. 11 is a broken transverse sectional view of a threaded work-piece on a greatly-enlarged scale.

The self-opening die-head shown in the accompanying drawings for purposes of making clear one form of the present invention, includes a body-member generally designated by the reference character 15, a chaser-operating sleeve 16, a tripping-sleeve 17, a latch-carrying ring 18, and an adjusting-nut 20.

The body-member 15 above referred to includes a relatively-large-dia-metered forward head-portion 21 from which rearwardly extends a relatively-small-dia-metered shank 22 formed integral with the said head-portion. Extending axially through both the head-portion 21 and the shank 22 of the body-member 15, is a clearance-

passage 23 which is increased in diameter toward its forward end in two steps, as is particularly well shown in Figs. 7 and 8.

The head-portion 21 of the body-member 15 is formed in its forward face with four (more or less) circumferentially-equidistant radial slots 24, in each of which is slidably mounted one of four similar thread-cutting chasers 25. The inner edge of each of the said chasers 25 is formed with a series of thread-cutting teeth 26 tapering forwardly and outwardly at an angle substantially corresponding to the desired angle of the threads to be cut upon a work-piece. The chasers 25 above referred to are retained in place in the slots 24 by four segmental plates 27 which are secured to the forward face of the said head-portion 21 by means of screws 28, as is shown in Fig. 1.

Each thread-cutting chaser 25 is provided adjacent its outer end with a rearwardly-projecting pin 29. Thrusting radially outwardly against the said pin 29 and hence also against the chaser 25 from which it extends, is a cup-shaped chaser-retracting plunger 30 (one for each chaser) mounted for axial reciprocation in a radial spring-pocket 31, one of which latter is formed in the head-portion 21 of the body-member 15 back of each of the slots 24 therein. Each of the plungers 30 is urged outwardly by a helical chaser-retracting spring 32 and is limited in its outward movement by a stop-pin 33 which projects forwardly from the head-portion 21 into the outer-portion of the adjacent spring-pocket 31, as is shown in Figs. 7 and 8.

Each of the thread-cutting chasers 25 is formed at its outer end with an inwardly-and-rearwardly-sloping cam-surface 34 which is engaged by one of four similarly-sloping cam-surfaces 35 formed respectively at circumferentially-equidistant points on the forward inner edge-portion of the chaser-operating sleeve 16 before referred to, and which has axial sliding movement on the body-member 15.

The forward-portion of the chaser-operating sleeve 16 is relatively-large and has its inner surface bearing upon the periphery of the head-portion 21 of the body-member 15. The rear-portion of the said chaser-operating sleeve is smaller in diameter and has its interior proportioned to slide upon the outer periphery of the latch-carrying ring 18 before referred to, as is especially well shown in Figs. 7 and 8.

The latch-carrying ring 18 is mounted upon the outer periphery of the shank 22 of the body-member 15 at a point immediately to the rear of the head-portion 21. The said latch-carrying ring has limited axial movement upon the shank 22 for purposes of effecting certain adjustments, but under operating conditions is stationary thereon and may be said to constitute a "body-unit" jointly with the said body-member 15.

The latch-carrying ring 18 is urged rearwardly so as to seat its rear face against the forward face of the adjusting-nut 20 by means of two helical springs 36-36. Each of the said springs 36-36 is mainly accommodated in one of two spring-pockets 37-37 opening through the forward face of the latch-carrying ring 18 respectively at diametrically-opposite points thereon. The said springs 36-36 thrust at their rear ends against the respective bottoms of the spring-pockets 37-37 and thrust at their forward ends against the rear face of the head-portion 21 of the body-member 15, to thus firmly seat 75

the latch-carrying ring 18 against the adjusting-nut 20.

The latch-carrying ring 18 is held against turning movement with respect to the chaser-operating sleeve 16 (and hence also with respect to the body-member 15) by means of a key 38 which is seated in the periphery of the said ring 18 and which extends with a sliding fit into a longitudinal keyway 39 formed in the interior of the rear-portion of the chaser-operating sleeve 16.

To provide for the adjustment of the adjusting-nut 20, it is formed internally with threads 40 interfitting with threads 41 formed upon the periphery of the shank 22 of the body-member 15. For purposes of locking the adjusting-nut 20 in a chosen position of adjustment on the shank 22, an internally-threaded clamping-shoe 42 is employed. The said clamping-shoe is mounted in a recess in the inner periphery of the adjusting-nut 20 and may be forced into tight engagement with the threads 41 on the shank 22 by means of a set-screw 43 threaded radially into the said adjusting-nut, as is especially well shown in Figs. 7 and 8.

The chaser-operating sleeve 16 is yieldingly urged rearwardly, for purposes as will hereinafter appear, by two helical retracting-springs 44-44. The said retracting-springs extend in parallelism with the axis of the die-head and are respectively located at diametrically-opposite points. The forward-portion of each of the retracting-springs 44-44 is accommodated in one of two rearwardly-opening spring-pockets 45-45 formed in the rear of the head-portion 21 of the body-member 15, as is especially well shown in Fig. 4. The rear end of each of the retracting-springs 44-44 is accommodated in one of two forwardly-opening spring-pockets 46-46 formed in the small-diametered rear-portion of the chaser-operating sleeve 16. Extending lengthwise in each of the retracting-spring 44-44 is one of two guide-pins 47-47 rigidly mounted in and projecting rearwardly from the head-portion 21 in axial relationship respectively with respect to the adjacent one of the spring-pockets 45-45.

For the purpose of holding the chaser-operating sleeve 16 against turning movement with respect to the body-member 15, while still permitting its relative axial movement with respect thereto, two coupling-pins 48-48 are employed. Each of the said coupling-pins is rigidly mounted at its rear end in the adjacent portion of the small-diametered rear part of the chaser-operating sleeve 16, as is shown in Fig. 5. The forward-portion of a given one of the said coupling-pins 48-48 is adapted to reciprocate in one of two coupling-passages 49-49 in the head-portion 21 of the body-member 15.

In the inner periphery of its small-diametered rear-portion, the chaser-operating sleeve 16 is formed with a substantially-semicircular eccentric groove 50, the forward wall of which stands substantially perpendicularly with respect to the longitudinal axis of the die-head and constitutes a rearwardly-facing latching-abutment 51. The said groove 50 is adapted to receive a substantially-semicircular latching-rib 52 formed upon the outer periphery of a substantially-semicircular latch-member 53. The forward face of the rib 52 just referred to also extends perpendicularly with respect to the longitudinal axis of the die-head and constitutes a forwardly-facing latching-abutment 54 which is adapted to engage with the rearwardly-facing latching-abutment 51 in the chaser-operating sleeve 16.

The substantially-semi-circular latching-abutment 54 on the latch-member 53 extends at an acute angle with respect to the forward face of the said latch-member. The rear face of the said latch-member extends in parallelism with the said front face, as is especially well shown in Figs. 7 and 8. Both the front and rear faces of the latch-member 53 are inclined slightly rearwardly with respect to the periphery of the latch-member, as the said faces progress inwardly toward the longitudinal axis of the body-member 15.

The latch-member 53 above referred to, is mounted for movement toward and away from the groove 50 in the chaser-operating sleeve 16, in a rearwardly-and-inwardly-inclined latch-guiding notch 55 formed in and extending transversely of the latch-carrying ring 18. The respective front and rear walls of the guide-notch 55 extend in parallelism with each other and are spaced apart just enough to receive the latch-member 53 between them with a smooth sliding fit.

The latch-member 53 is urged outwardly by two helical latch-springs 56—56, each of which is seated in one of two spring-pockets 57—57 respectively formed in the opposite side walls of the latch-carrying ring 18 at the bottom of the notch 55, as is especially well shown in Fig. 6. The upper end of each of the latch-springs 56—56 bears against the adjacent under-face portion of the segmental latch-member 53.

Returning now to the tripping-sleeve 17, it will be noted by reference to Fig. 6 that a key 58 is installed between the said tripping-sleeve and the chaser-operating sleeve 16. The connection provided by the key 58 is such as to hold the chaser-operating tripping-sleeve 17 against turning-movement on the outer periphery of the chaser-operating sleeve 16, while permitting relative axial movement between the two said sleeves.

To provide for the disengagement of the latching-abutment 54 of the latch-member 53 from the latching-abutment 51 in the chaser-operating sleeve 16, the said chaser-operating sleeve is formed in its rear portion with a substantially-radial guide-passage 59 in which is mounted a ball 60, or other suitable transmitting-member. The inner-portion of the ball 60 presses against the outer periphery of the latching-rib 52 of the latch-member 53, while the outer-portion of the said ball rests against a forwardly-and-inwardly-inclined cam-surface 61 constituting the sloping forward wall of an arcuate recess 62 formed in the interior of the rear-portion of the tripping-sleeve 17.

In the outer surface of its rear-portion, the axially-movable tripping-sleeve 17 is formed with a circumferential groove 63 into which a suitable stop-member may extend, in a manner well known in the art.

For the purpose of limiting the rearward movement of the chaser-operating sleeve 16 from the position in which it is shown by full lines in Figs. 7 and 8 into its retired position in which it is indicated by the broken lines 16a in Fig. 8, the adjusting-nut 20 is formed with a transverse groove 64 in which is located an arcuate stop-member 65. The said stop-member is pivotally mounted at one end upon a pivot-pin 66 mounted in the adjusting-nut. The opposite end of said stop-member is pressed outwardly by a plunger 67 mounted for axial reciprocation in a pocket 68 extending perpendicularly with respect to and opening through the portion of the bottom wall

5 of the groove 64 opposite the pivot-pin 66. Interposed between the inner end of the plunger 67 and the bottom of the pocket 68, is a helical spring 69.

At its extreme rear end, the adjusting-nut 20 is formed on its periphery with an annular stop-flange 70 against which the rear face of the chaser-operating sleeve 16 is adapted to abut when it is moved into its chaser-releasing position as indicated by the broken line 16b under conditions as will hereinafter appear.

Operation

For purposes of description, let it be assumed that the self-opening die-head above described is mounted by means of its shank 22 in the rotating chuck of a thread-cutting machine, and that the said die-head is advanced axially toward a work-piece arranged coaxially with respect to the die-head. The said advancement of the die-head will take place after the chaser-operating sleeve 16 has been locked in its forward position, to thereby hold the group of thread-cutting chasers 25 inwardly in position in readiness for cutting the threads as is shown in the drawings.

As the die-head, including its tripping-sleeve 17, is advanced axially toward the work-piece, or vice versa, the teeth 26 of the thread-cutting 20 chasers 25 will engage with the work-piece and will cut a tapering thread thereon as the said axial movement continues.

Just before the desired length of tapered thread has been cut upon the work-piece, the tripping-sleeve 17 may have its forward axial movement checked while the remainder of the die-head continues to advance axially. The checking referred to may be effected by means of any suitable stop such, for instance, as a stop-member 40 entered into the annular groove 63 in the said tripping-sleeve.

After the forward axial movement of the tripping-sleeve 17 has been checked as just described, the remaining elements of the die-head 45 will still continue their forward axial movement, with the result that the ball 60 will be forced radially inwardly by the cam-surface 61 in the tripping-sleeve. The inward movement of the ball 60 will, in turn, force the latch-member 53 50 inwardly until it reaches the position shown in Fig. 8.

Now, inasmuch as the above-described inward movement of the latch-member 53 is along a slightly-rearwardly-inclined path, the latching-abutment 54 of the said latch-member will move slightly rearwardly during the described inward movement of the said latch-member of which it forms a part. This slight rearward movement of the latching-abutment 54 will permit a corresponding slight rearward movement of the chaser-operating sleeve 16 under the urge of its retracting-springs 44—44, and hence will permit the slight outward movement of the chasers 25 under the urge of their respective chaser-retracting springs 32, all while relative rotation is taking place between the die-head and the work-piece being threaded.

For a better understanding of the effect produced by the slight preliminary or let-off movement of the chasers 25 as just above described, attention may be called to the fact that were the said chasers permitted to retire abruptly while still engaged in a thread-cutting operation, a shoulder such as is indicated by the broken line 75 75 71, would be produced upon a work-piece 12 as

is illustrated in Fig. 11. However, inasmuch as the retirement of the chasers is effected gradually as a preliminary step to their complete release (to be presently described), the shoulder 71 will be erased and a substantially perfect tapered thread will be produced upon a work-piece such as 72.

Immediately following the inward movement of the latch-member 53 into the position in which it is shown in Fig. 8, the outer edge of its latching-abutment 54 will clear the inner edge of the latching-abutment 51 in the chaser-operating sleeve 16, whereupon the retracting-springs 44-44 will assert themselves and snap the said chaser-operating sleeve rearwardly into the position in which it is represented by the broken line 16a in Fig. 8. The described rapid rearward movement of the chaser-operating sleeve 16 will be checked by the engagement of the rear face of the said sleeve with the forward face of the pivotal arcuate stop-member 65. The described rapid rearward movement of the chaser-operating sleeve 16 will also retire its cam-surfaces 35, thereby permitting each of the chasers 25 to be moved radially outwardly by their respective chaser-retracting springs 32. The die-head structure and the now-threaded work-piece may be axially separated without requiring an unthreading operation.

When it is desired to remove the chasers 25 from the body-member 15, the pivotal stop-member 65 may be pressed inwardly against the tension of its spring 69, to thus clear the inner rear-portion of the chaser-operating sleeve 16. The said chaser-operating sleeve will now be moved rearwardly by its retracting-springs 44-44 until the chaser-operating sleeve 16 reaches the position indicated by the broken lines 16b in Fig. 8, wherein the rear end of the said sleeve 16 is abutted against the stop-flange 70 of the adjusting-nut 20. When fully retired as just described, the forward end of the chaser-operating sleeve 16 will lie slightly to the rear of the rear faces of the chasers 25, whereby the said chasers may be removed radially from the body-member 15.

By the construction and arrangement of parts exemplified in the accompanying drawings and described above, the gradual shoulder-erasing or let-off movement of the chasers may be accomplished without the liability that the chasers will be unintentionally fully retired by the failure of the latch-member to remain latched when it is intended that it should. This reliability of operation is secured despite severe shock and vibration to which the die-head may be subjected in operation.

The invention may be carried out in other specific ways than those herein set forth without departing from the spirit and essential characteristics of the invention, and the present embodiments are, therefore, to be considered in all respects as illustrative and not restrictive and all changes coming within the meaning and equivalency range of the appended claims are intended to be embraced therein.

I claim:

1. A self-opening die-head, including in combination: a body-unit having a front and provided with a latch-guiding recess having parallel front and rear walls both of which extend inwardly from a lateral outer surface of the body-unit toward the longitudinal axis thereof but at an angle which progresses away from the said front as it progresses inwardly toward the said axis; a plurality of thread-cutting chasers car-

ried by and movable with respect to the front of the said body-unit toward and away from the longitudinal axis thereof; a chaser-operating member operatively-associated with the said chasers and provided with a rearwardly-facing latching abutment, the said member being movable in a direction longitudinally of the said body-unit into and out of position to hold the said chasers in their advanced or thread-cutting position; spring-means yieldingly urging the said chaser-operating member rearwardly into a position wherein the said chasers are retired into inoperative position; and a latch-member having parallel front and rear walls respectively engaging with the inclined front and rear walls of the latch-guiding recess in the said body-unit, the said latch-member being provided with a forwardly-facing latching-abutment releasably engageable with the rearwardly-facing latching-abutment of the said chaser-operating member and disengageable therefrom by an inward and rearward movement of the latch-member in the latch-guiding recess of the body-unit, the latching-abutment of the latch-member extending in a plane more nearly perpendicular with respect to the longitudinal axis of the said body-unit than the front and rear walls of the latch-guiding recess therein.

2. A self-opening die-head, including in combination: a body-unit having a front and having a cylindrically-contoured portion formed in a direction transverse of its longitudinal axis with a latch-guiding recess intersecting the periphery thereof, the said latch-guiding recess having parallel front and rear walls both of which extend inwardly from the periphery of the said cylindrically-contoured portion toward the longitudinal axis of the die-head but at an angle which progresses away from the said front as it progresses inwardly toward the said axis; a plurality of thread-cutting chasers carried by and movable with respect to the front of the said body-unit toward and away from the longitudinal axis thereof; a chaser-operating sleeve encircling the cylindrically-contoured portion of the said body-unit and provided with a rearwardly-facing latching-abutment, the said sleeve being operatively-associated with the said chasers and movable in a direction longitudinally of the said body-unit into and out of position to move the said chasers in their advanced or thread-cutting position; spring-means yieldingly urging the said chaser-operating member rearwardly into a position wherein the said chasers are retired into inoperative position; and a latch-member having a cylindrically-contoured outer surface and having parallel front and rear walls respectively engaging with the inclined front and rear walls of the latch-guiding recess in the cylindrically-contoured portion of the said body-unit, the said latch-member being provided with a forwardly-facing latching-abutment releasably engageable with the rearwardly-facing latching-abutment of the said chaser-operating member and disengageable therefrom by an inward and rearward movement of the latch-member in the inclined latch-guiding recess of the body-unit, the latching-abutment of the latch-member extending in a plane more nearly perpendicular with respect to the longitudinal axis of the body-unit than the front and rear walls of the latch-guiding recess therein.

3. A self-opening die-head, including in combination: a body-member having a front portion; a latch-carrying member carried by the said

body-member and adjustable axially with respect thereto, the said latch-carrying member being provided with a latch-guiding recess having parallel front and rear walls both of which extend inwardly from a lateral outer surface of the latch-carrying member toward the longitudinal axis thereof but at an angle which progresses away from the said front as it progresses inwardly toward the said axis; a plurality of thread-cutting chasers carried by and movable with respect to the front portion of the said body-member toward and away from the longitudinal axis thereof; a chaser-operating member operatively associated with the said chasers and provided with a rearwardly-facing latching-abutment, the said chaser-operating member being movable in a direction longitudinally of the said body-member into and out of position to hold the said chasers in their advanced or thread-cutting position; spring-means yieldingly urging the said chaser-operating member rearwardly into a position wherein the said chasers are retired into their inoperative position; and a latch-member having parallel front and rear walls respectively engaging the inclined front and rear walls of the latch-guiding recess in the said latch-carrying member, the said latch-member being provided with a forwardly-facing latching-abutment releasably engageable with the rearwardly-facing latching-abutment of the said chaser-operating member and disengageable therefrom by an inward and rearward movement of the latch-member in the inclined latch-guiding recess of the latch-carrying member, the latching-abutment of the latch-member extending in a plane more nearly perpendicular with respect to the longitudinal axis of the body-member than the front and rear walls of the latch-guiding recess in the latch-carrying member.

4. A self-opening die-head, including in combination: a body-member having a front portion; a cylindrically-contoured latch-carrying member carried by the said body-member and adjustable axially thereof, the said latch-carrying member being formed in a direction transverse of its longitudinal axis with a latch-guiding recess intersecting the periphery thereof, the said latch-guiding recess having parallel front and rear walls both of which extend inwardly

from the periphery of the said latch-carrying member toward the longitudinal axis of the said die-head but at an angle which progresses away from the said front as it progresses inwardly toward the said axis; a plurality of thread-cutting chasers carried by and movable with respect to the front portion of the said body-member toward and away from the longitudinal axis thereof; a chaser-operating sleeve encircling the cylindrically-contoured latch-carrying member and provided with a rearwardly-facing latching-abutment, the said sleeve being operatively associated with the said chasers and movable in a direction longitudinally of the said body-member into and out of position to move the said chasers into their advanced or thread-cutting position; spring-means urging the said chaser-operating sleeve rearwardly; and a latch-member having a cylindrically-contoured outer surface and having parallel front and rear walls respectively engaging with the inclined front and rear walls of the latch-guiding recess in the cylindrically-contoured latch-carrying member, the said latch-member being provided with a forwardly-facing latching abutment releasably engageable with the rearwardly-facing latching-abutment of the said chaser-operating member and disengageable therefrom by an inward and rearward movement of the said latch-member in the inclined latch-guiding recess of the latch-carrying member, the latching-abutment of the latch-member extending in a plane more nearly perpendicular with respect to the longitudinal axis of the body-member than the front and rear walls of the latch-guiding recess in the latch-carrying member.
